[57] CLAIM

The ornamental design for a toy building element, as
shown and described.

DESCRIPTION

FIG. 1 is a top perspective view of the toy building
element showing my new design;

FIG. 2 is a bottom perspective view thereof;

FIG. 3 is a left side elevational view thereof, the right
view being identical;

FIG. 4 is a front elevational view thereof, the rear side
being identical;

FIG. 5 is a bottom plan view thereof; and,

FIG. 6 is a top plan view thereof.

FIG. 1

FIG. 2

FIG. 5

FIG. 4
